UNITED STATES PATENT OFFICE.

MERTON ROY GIPPLE, OF PRAIRIE GROVE, ARKANSAS.

MUFFLER FOR INTERNAL-COMBUSTION MOTORS.

1,085,203.

Specification of Letters Patent.

Patented Jan. 27, 1914.

Application filed April 17, 1913. Serial No. 761,767.

To all whom it may concern:

Be it known that I, MERTON ROY GIPPLE, citizen of the United States, residing at Prairie Grove, in the county of Washington and State of Arkansas, have invented certain new and useful Improvements in Mufflers for Internal-Combustion Motors; and I do declare the following to be a full, clear, and exact description of the invention, such as will enable others skilled in the art to which it appertains to make and use the same.

This invention relates to improvements in exhaust mufflers for internal combustion motors.

One object of the invention is to provide a muffler in which the exhaust gases resulting from the explosions of the motor will be diffused in passing through the muffler and will thus be caused to discharge silently therefrom.

Another object is to provide a muffler of this character which will be simple, strong, durable and inexpensive in construction, efficient and reliable and in which there will be practically no back pressure.

With these and other objects in view, the invention consists of certain novel features of construction, and the combination and arrangement of parts as will be more fully described and claimed.

In the accompanying drawings: Figure 1 is a central longitudinal section of my improved muffler; Fig. 2 is an end elevation of one end thereof; Fig. 3 is a cross section taken on the line 3—3 of Fig. 1.

In the embodiment of the invention, I provide a cylinder 1 which may be of any suitable length and diameter and open at its ends as shown. The open ends of the cylinder are closed by convex heads or caps 2 and 3 which fit over the ends of the cylinder and are firmly secured in position thereon by a central longitudinally disposed tie rod or bolt 4 which extends through the center of the caps or heads and through the center of the cylinder as shown. One end of the bolt or head 4 is provided with a head which engages the outer side of the cap 2 while the other end of the rod or bolt has thereon a nut 5 which is screwed up into engagement with the outer end of the head 3 and thereby clamps the heads into engagement with the ends of the cylinder. In the head 2 at one side of the center thereof is formed an inlet

opening 6 which is surrounded by an outwardly extending interiorly threaded flange or socket 7 adapted to receive the end of the exhaust tube of the motor. In the head 3 and preferably in line with the aperture 6 of the head 2 is a discharge aperture 8 which is surrounded by an outwardly extending interiorly threaded flange or socket 9 into which is adapted to be screwed a discharge pipe or nipple (not shown) but by means of which the exhaust may be discharged at any desired point.

Arranged in the cylinder 1 near the inlet end thereof is an inclined baffle or deflecting plate 10 which extends from one side to the other of the cylinder and inwardly to a point a slight distance beyond the center of the cylinder as shown. The inner edge of the baffle plate 10 is preferably curved or turned inwardly as shown. The outer portion of the plate is braced and securely fastened to the inner sides of the cylinder by short lugs 11 which are riveted or otherwise firmly secured to the side of the cylinder as shown. In the opposite end of the cylinder and extending inwardly from the opposite side thereof from the baffle plate 10 is a baffle plate 12. The plate 12 extends inwardly to a slight distance beyond the center of the cylinder and has its inner edge turned outwardly toward the adjacent end of the cylinder as shown. The plate 12 is fastened near its outer edge to the opposite sides of the cylinder by lugs 13 which are riveted or otherwise secured to the inner side of the cylinder. Between the outer baffle plates 10 and 12 are arranged intermediate baffle plates 14 and 15 which are spaced equal distances apart and from the plates 10 and 12 as shown. The plates 14 project inwardly from opposite sides of the cylinder and to points slightly beyond the center of the cylinder, said plates being inclined in opposite directions. The plate 14 also inclines in a direction opposite to the adjacent plate 10 and in substantially the same direction as the opposite end plate 12, while the plate 15 extends in an opposite direction from the adjacent end plate 12 and in substantially the same direction as the opposite end plate 10. The plates 14 and 15 are secured near their inner edges to the sides of the cylinder by lugs 16 which are riveted or otherwise fastened to the cylinder as shown. The inner edges of the 110

plates extend squarely across the cylinder and are not turned like the edges of the outer plates.

By constructing my improved muffler as herein shown and described it will be seen that a tortuous or indirect passage is formed in the cylinder through which the exhaust gases entering the inner end thereof must pass before being discharged from the outer 10 end of the cylinder. In passing through the tortuous passage the exhaust gases are diffused and prevented from being forcibly ejected from the outer end of the muffler and thus causing the undesirable noise 15 which results from the direct discharge of the exhaust gases from an explosive motor. The arrangement of the baffle plates which form the tortuous passage through the motor will not however cause any perceptible back 20 pressure of the gases passing therethrough.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described my invention, what I claim is:

1. In an automobile muffler of the character described, the combination of a tubular 35 gas receiving receptacle having inlet and exhaust openings at its opposite ends; baffle plates arranged within said chamber, said plates having therein openings registering with the axial center of the latter, attaching 40 lugs arranged in triangular relation on said plates, whereby the latter may be securely fastened within said chamber and

sufficiently reinforced to withstand the expanding force of the entering gas, and a tie rod extending centrally and longitudinally 45 through said chamber and through the opening in said baffle plates, whereby said plates may be further braced to resist the force of said gases.

2. In an automobile muffler of the character described, the combination of a tubular gas receiving receptacle having inlet and exhaust openings at its opposite ends, outer baffle plates arranged within said chamber adjacent its opposite ends and projecting 55 inwardly in opposite directions beyond the axial center thereof, said plates having their free ends curved whereby the direction of the expanding gases may be reversed and directed to the walls of said chamber, inner 60 baffle plates arranged intermediate said outer baffle plates and projecting inwardly in opposite directions beyond the axial center of said chamber, said inner and outer baffle plates having therein openings registering 65 with said axial center, attaching lugs arranged in triangular relation on said plates, whereby the latter may be securely fastened within said chamber and sufficiently reinforced to withstand the expanding force of the entering gas, and a tie rod extending centrally and longitudinally 70 through said chamber and through the opening in said baffle plates, whereby the latter may be further braced to resist the force of said gases.

In testimony whereof I have hereunto set my hand in presence of two subscribing witnesses.

MERTON ROY GIPPLE.
